UNITED STATES PATENT OFFICE.

WILLIAM PHENIX, OF CHICAGO, ILLINOIS, ASSIGNOR OF ONE-HALF TO
GEORGE JUDGE, OF SAME PLACE.

MEANS FOR CARRYING TRACTION-CABLES AROUND CURVES.

SPECIFICATION forming part of Letters Patent No. 337,786, dated March 9, 1886.

Application filed June 22, 1885. Serial No. 169,363. (No model.)

To all whom it may concern:

Be it known that I, WILLIAM PHENIX, of Chicago, county of Cook, and State of Illinois, have invented certain new and useful Improvements in Means for Carrying Cables Around Curves, of which the following is a full, clear, and exact description, that will enable others to make and use the same, reference being had to the accompanying drawings, forming a part of this specification.

The object of this invention is to provide an improved means for carrying traction-cables operating street-cars around curves; and it consists of certain novel features in the construction, combination, and arrangement of devices, as will be hereinafter set forth.

Figure 1 is an end elevation of the cable-conduit embodying my improved features; Fig. 2, a plan of a curved section of the roadway; Fig. 3, a vertical section of a double sheave; Fig. 4, a plan of two of the pulleys and means for supporting the same between the conduit-yokes; Fig. 5, a view of the under side of the same, and Fig. 6 an edge view of one of the bars supporting the double sheaves; Fig. 7, a detached detail.

Referring to the drawings, A represents the conduit-cable passage; A', the yoke; A², a supporting plate-flange riveted to said yoke, the outer top edges of which support the track-rails. The double sheave-wheel consists of the upper sheave, B, and the lower sheave, B', both loosely mounted on the vertical stationary shaft B². The upper square end of this shaft is secured and retained in place by being inserted in an aperture formed in the junction of the two arms C C'. The outer end of the arm C is bent upward and bolted to one of the Z-slot irons B³, as shown in Figs. 1 and 4. The corresponding arm, C', extends off at right angles, and is bolted to the yoke-flange A². The lower square end of the shaft B² is inserted in the socket-bearings C², formed on the bar or bars D, supporting the sheaves between the conduit-yokes. The bearings C² are of a truncated-cone shape, as shown in different figures of the drawings. The lower part of the shaft B² is of a greater diameter than the upper part, thus forming the central shoul-

der, a, on which rests the under side of the stationary collar a', separating the hubs of the two sheaves. The upper end of the hub of the sheave B is cupped out, so as to receive a lubricant, the lower end being provided with a shallow recess, which projects down a little way over the upper side of the collar a'. The under side of this collar is also recessed, the annular flaring edge a² extending down over the upper beveled end of the hub of the lower sheave, B', as shown in Fig. 3. The lower end of the hub of the sheave B' is likewise recessed, and is provided with the annular flaring rim a³, which corresponds to the contour of the socket-bearing C². By this arrangement the sheaves are retained in proper relative position and independent of each other, and the dirt and grit prevented from getting into the bearings. The lower sheave, B', is provided with a wide face, a⁴, extending upward from the cable-groove, which is located in the extreme lower part of the sheave-wheel, as shown in Fig. 3. This wide surface on the lower sheave provides a riding-surface for the outside cable when not in contact with the grip-sheave d², as this cable should have some play in order to relieve the same of any undue strain. These two sheaves are adapted to rotate in a horizontal plane and independent of each other, and are intended to be rotated in opposite directions by the frictional contact of the two parts of an endless cable having a corresponding movement.

Fig. 1 shows the relative position of the sheaves to the moving cable-grip D', and Fig. 2 the arrangement of the series of sheaves to ease the cable around a curve. The ends of the bar D are supported by and bolted to the angle-brackets b, which are in turn riveted to the yoke-flange, as shown in Figs. 1 and 6. The brackets b are provided with the elongated aperture b', through which the bolts b² are inserted, by which arrangement the bars D are adapted to have a lateral adjustment, so as to bring the series of sheave-wheels into a true alignment relative to each other. The adjustable keys d are inserted between the ends of the bar or bars D and the yoke-flange, and serve the purpose of stiffening the struct-

ure and relieving the bolts b^2 of undue strain, and readily permit of the bars being removed at any time by driving out the keys and taking out the holding-bolts, which could not be done were they made long enough to bear against each yoke-flange, on account of the endwise strain.

The cable-carrying sheaves may be removed singly at any time for repairs, and readily re-placed without having to stop the cable, by simply taking out the bolts and removing the arms C C'.

d^1 d^2 are the cable-carrying sheaves attached to the car-grip, and d^3 the cable, which remains in the sheave d^1 and runs in the horizontal sheave B, both back of and in advance of the grip when rounding a curve. Two sets of the sheaves B B' are arranged in the space between each of the yoke-flanges, as shown in Fig. 2, the radial dotted lines representing the position of the yoke-flanges. By this arrangement the friction and wear on the cable is reduced to a minimum, and repairs on the means employed for carrying cables around curves greatly facilitated.

Having thus described my invention, what I claim as new, and desire to secure by Letters Patent, is—

1. The combination, with a traction-cable, of a system or series of sheave-wheels rotating in a horizontal plane and arranged in pairs on the same shaft, the single companion sheave of each pair being adapted to rotate in opposite directions, substantially as and for the purpose set forth.

2. The combination, with the yoke-flanges,

of the bar D, provided with the socket-bearings C², and the means described for adjustably securing and retaining said bar in relation to said yoke-flanges, substantially as and for the purpose set forth.

3. The combination, with the bar D, provided with the socket-bearings C², of the vertical stationary shaft B² and the companion arms C C', whereby said shaft is retained in place, substantially as set forth.

4. The combination, with the vertical stationary shaft B², provided centrally with the shoulder a, of the collar a', the upper sheave-wheel, B, having the under side of the hub 50 recessed, as described, and the lower sheave-wheel, B', said sheave-wheels being adapted to rotate independent of each other, substantially as and for the purpose set forth.

5. The combination, with the stationary shaft B², of the collar a', having the under side recessed and provided with the flaring edge a², and the lower sheave-wheel, B', having part of the hub beveled and fitting inside of said flaring edge, substantially as and for the purpose set forth.

6. The combination, with the wheel B', having the wide face a⁴ and provided on the lower end of the hub with the annular flaring rim a³, of the socket-bearing C², having a beveled contour, substantially as and for the purpose set forth.

WILLIAM PHENIX.
